Exercise

William W. Jackson by Order of the Ad

UNITED STATES PATENT OFFICE.

WILLIAM W. JACKSON, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 18,269, dated April 24, 1888.

Application filed March 31, 1888. Serial No. 209,912. Term of patent 7 years.

To all whom it may concern:

Be it known that I, WILLIAM W. JACKSON, (assignor to THE MACKELLAR, SMITHS & JORDAN COMPANY,) of the city and county of Philadelphia, Pennsylvania, have invented a new and original Design for a Font of Printing-Type, of which the following is a specification.

The nature of my design is clearly shown in the accompanying typographic impression, to which reference is made; and it consists of an unshaded letter provided with the scroll terminations, as shown.

In the A, C, H, L, Q, R, X, and Z the scroll termination is found upon the right of the letter, at the base. In the B, D, P, R, and Z the scroll termination is found upon the left of the letter, at the top. Both terminations of the E and K and the upper termination of the F, G, N, S, T, U, V, W, X, and Y upon the right have the scroll ornamentation. The scroll termination is also found in the J and S at the base upon the left hand. The up-and-down portion of the B, D, H, I, K, L, M, P, R, and Y is concaved at top and bottom, and the A, 15 J, N, U, V, W, and X are concaved above, as shown. The C and O are ornamented above by the semi elliptical curve with central dot. The upper portion of the Q is ornamented by the central dot. The cross-line of the A consists of a horizontal line extending upon the left of the up-and-down portion. The cross-line of the H consists of the flourish with dot termination.

The character of the design as nearly as possible is preserved in the lower-case and in the numerals. In connection with the font are shown two typographic affixes. The one shown upon the left of the numerals consists of a rosette-like figure shaded by a light line, the groundwork of which is heavy and supports a light many-pointed figure, in the center of which is placed a heavy dot surrounded by a circle. That upon the right of the numerals consists of two light circles, between 40 which is placed a heavy circle. From the interior of the inner light circle projects the

petal-like figures, and from the right of the outer light circle project the flourishes, as shown.

Having now described my invention, I claim 50 as new—

The design for a font of printing-type, as shown and described, the same consisting of an unshaded letter provided with the scroll terminations, as shown, in the A, C, H, L, Q, 55 R, X, and Z the scroll termination found upon the right of the letters at the base, in the B, D, R, P, and Z the scroll termination found upon the left of the letter at the top, both terminations of the E and K and the upper 60 termination of the F, G, N, S, T, U, W, X, and Y upon the right having the scroll ornamentation, the scroll termination also found in the J and S at the base upon the left hand, the up-and-down portion of the B, D, H, I, K, 65 L, M, P, R, and Y concaved at top and bottom and the A, J, N, U, V, W, and X concaved above, the C and O ornamented above by the semi elliptical curve with central dot, the upper portion of the Q ornamented by the 70 central dot, the cross-line of the A consisting of a horizontal line extending upon the left of the up-and-down portion, the cross-line of the H consisting of the flourish with dot termination, the character of the design as nearly as 75 possible preserved in the lower-case and numerals, and the font provided with two typographic affixes, the first consisting of a rosette-like figure shaded by a light line, the groundwork of which is heavy and supports a light 80 many-pointed figure, in the center of which is placed a heavy dot surrounded by a circle, while the other consists of two light circles, between which is placed a heavy circle, from the interior of the inner light circle projecting 85 the petal-like figures, and from the right of the outer light circle the flourishes.

WM. W. JACKSON.

In presence of—

J. H. HINCHMAN,
C. F. HUCH.
